UNITED STATES PATENT OFFICE.

ARTHUR HESS AND SAMUEL L. MARSH, OF LOS ANGELES, CALIFORNIA.

FLOOR DRAIN.

Application filed November 14, 1922. Serial No. 600,844.

To all whom it may concern:

Be it known that we, ARTHUR HESS and SAMUEL L. MARSH, both citizens of the United States, and residents of Los Angeles, in the county of Los Angeles and State of California, have invented new and useful Improvements in a Floor Drain, of which the following is a specification.

This invention relates to a drain for flooring made of cementitious material, such as concrete or compositions, and pertains particularly to the provision of a self-contained drain and trap. The employment of such drain is advantageous in shower, wash, or toilet room floors, in hospitals and other institutions where water or like liquid is to be drained from the floor into a sewer, in the roofs of buildings, in refrigerators and for many other purposes.

The expansion and contraction of cementitious floors will not permit a watertight joint around the rim or collar. To overcome this difficulty, drains have been constructed with annular cups to catch the seepage around the rim and lead it back into the drain. The present invention contemplates a structure of this character and has for its primary object the provision of a combined drain and trap having structural features which make it compact, easily installed, simple, economical, long lived, and easily cleaned.

These objects together with other objects and corresponding accomplishments are obtained by means of the embodiment of our invention illustrated in the accompanying drawing, in which:

The figure shows a perspective view with a section broken out to show the internal construction.

Referring more particularly to the drawing, a tubular outlet is indicated by 1. Preferably formed integral therewith and extending laterally intermediate the ends of the outlet is a cup 2. This cup has a side wall flaring outwardly. Extending above the top of the outlet is a bridge 3.

Disposed over the outlet is a double hood in the nature of an inverted double cup serving as a strainer and as a portion of a trap. This hood comprises a top wall 4 intended to be set flush with the floor. Extending downwardly therefrom is an outer cylindrical wall 5 having a serrated edge. The hood is attached to the bridge by means of a set screw 6, and the relative dimensions

should be such that the bottom of the wall 5 rests upon the bottom of the cup 2 so that water may pass thereunder. Disposed within the outer wall 5 concentric therewith and spaced therefrom is an inner wall 7. This wall ends short of the bottom wall of the cup 2 so as to provide a trap, one arm of which is the annular chamber between the walls 5 and 7, and the other arm of which is the annular chamber between the walls 1 and 7. These chambers are so arranged that the trap is absolutely non-siphoning. Communicating with the space between the walls 5 and 7 are a number of strainer holes 8 for the admission of the water to be drained.

In installing the drain, the cup is embedded within the cement or other composition flooring so that it is filled and is below the surface thereof. The joint between the flooring and the rim or wall 5 is open at the surface so that water may seep therethrough. Water which does seep through cannot pass the cup and will enter the inlets under the outer wall instead of draining through the floor to the ceiling beneath. The trap prevents sewer gas from passing up into the room through the drain holes. In case of stoppage, the set screw 6 can be removed and the hood withdrawn, permitting cleaning.

What we claim is:

1. A drain comprising a tubular outlet, a cup extending laterally therefrom intermediate its ends, an inner hood wall closed at the top nested over and spaced above the top of said outlet, and an outer hood wall spaced from said inner hood wall and having seepage inlets along the lower edge, there being drainage inlets to the space between said walls, said outlets and said hood walls forming a bell trap.

2. A drain comprising a tubular outlet, a cup extending laterally therefrom intermediate its ends, a double hood nested over said outlet, said hood comprising spaced cylindrical walls and a top, the inner cylindrical wall ending short of the bottom of the outer cylindrical wall and the top thereof being imperforate, there being seepage inlets around the lower edge of said outer wall and there being drainage inlets to the space between said walls, said outlets and said hood forming a bell trap.

3. A drain comprising a tubular outlet, a cup extending laterally therefrom intermediate its ends, a hood detachably secured

to said outlet, said hood comprising an inner hood wall closed by an imperforate top and nested over and spaced from the top of said outlet, and an outer hood wall spaced 5 from said inner hood wall and having seepage inlets along the lower edge thereof, there being drainage inlets to the space between said walls, said outlet and said hood forming a bell trap.

10 4. A drain comprising a tubular outlet, a cup extending laterally therefrom intermediate its ends, a double hood detachably secured over said outlet, said hood comprising two spaced cylindrical walls and a top,

the inner cylindrical wall ending short of 15 the bottom of the outer cylindrical wall and the top thereof being imperforate, the outer cylindrical wall having seepage inlets between its lower edge and the cup, there being drainage inlets to the space between said 20 walls, said outlet and said hood forming a trap.

In witness that we claim the foregoing we have hereunto subscribed our names this 4th day of November, 1922.

ARTHUR HESS,
SAMUEL L. MARSH.
